[57] CLAIM

The ornamental design for a combined shirt pocket cuspidor and ashtray or similar article, as shown and described.

DESCRIPTION

FIG. 1 is a perspective view of a combined shirt pocket cuspidor and ashtray or similar article, mouth piece and neck portion in closed position, showing my new design;

FIG. 2 is a front elevational view thereof showing the integral hinged lid over the mouth piece in the closed position;

FIG. 3 is a top plan view thereof;

FIG. 4 is a bottom view thereof;

FIG. 5 is a side elevational view thereof; and

FIG. 6 is a front elevational view thereof illustrating the neck portion in extended position and with portions cut away as indicated by line 6—6 of FIG. 3.

The broken line showing of a logo symbol is for illustrative purposes only and forms no part of the claimed design.
